UNITED STATES PATENT OFFICE

EVARISTE E. TALBOT, OF FALL RIVER, MASSACHUSETTS

PARALLEL PICKER-STICK MOTION

Application filed January 20, 1928. Serial No. 248,076.

This invention relates to mounting for picker sticks and includes a motion transmitting device capable of being applied to any loom of standard type. As illustrative there-
5 of I have shown a form of practical efficiency.

In the drawings:

Fig. 1 is a side view of my device showing the throw limit and parallel reverse travel of the picker stick.

10 Fig. 1^a is a diagrammatical view of a part of my device.

Fig. 2 is a view of the side opposite to that shown in Fig. 1.

15 Figs. 3 and 4 are front and rear end views, respectively.

Figs. 5 and 6 are the picker stick strap and the casting, respectively.

Fig. 7 is a view of the assembled spring box.

20 Fig. 8 is a view of the anchor side of the spring box.

Fig. 8^a is an inside view of the detached anchor part.

Fig. 9 is a view of the compensating cover of spring box.

25 Fig. 9^a is an inside view of the detached compensating cover.

Fig. 10 is a section on the line 10—10, Fig. 8^a, and

30 Fig. 11 is a partial section on the line 11—11, of Fig. 9^a.

In accordance with my invention the picker stick S may be mounted on the usual rocker shaft R. The bracket casting 1 has a rearwardly projecting sleeve 1¹, which receives the rock shaft R of the lay of the loom as indicated at 2 in Fig. 6. It is tapped to receive the set screws 3 by which means it is firmly held on said rock shaft. Upwardly extending sides 1^a and 1^b of the casting 1 provide a bearing for a stud 4 and its loose sleeve 5. These lateral sides 1^a and 1^b supporting the stud 4 at each end steady the stick S. They act as lateral guides and prevent any twisting tendency on the part of the stick so that the alignment of the stick end is preserved and the blow is struck always at the same point.

50 Slidably mounted on the stud sleeve 5 is an elongated strap 6 slotted as at 7. This strap is attached to the picker stick as indicated

at 6¹ and 6². The bottom end of the strap 6 is provided with a pivot bearing 6^a for the post 8 on the compensating cover 9 of the spring box 10.

Hooked at 11¹ to fasten over an edge 10¹ of 55 a slot in the anchor side of the spring box 10 is a torsion spring 11. This torsion spring, best shown in Figs. 7, 8 and 10, is engaged at its opposite end at 11² over an edge 9¹ of the compensating cover 9.

60 When assembled the bolt 12 passes through the compensating cover of the spring box (shown in Figs. 6, 9, 9^a, and 11) and through a cored sleeve 13 of the anchor side of the spring box and on through an adjustment 65 slot 1^c, in the casting, as shown in Figs. 1, 3, and 4. The cord sleeve 13 fits loosely inside a sleeve 14 which is integral with said compensating cover of the spring box.

65 On the outside periphery of the anchor side 70 of the spring box 10 are a plurality of notches 10^a. The shoulders of said notches provide a convenient engaging means for rotating the box 10 relative to the cover 9 to tighten the torsion spring 11.

75 The spring 11 is drawn around cog-shaped shoulders 15 on the sleeve 14 at the forward throw of the picker stick, which provides a tension means for the return throw of said picker stick.

80 I have not attempted to indicate in the drawings any type of picker stick drive, as such may be of any standard type.

85 As I have attempted to show in Fig. 1^a, the movement of compensating cover 9 one-half of the arc of its revolution, as indicated by the arrow d, drops the pivot 8 a distance b—b and positions sleeved stud 4 at the top of the elongated slot 7, all of which compensates for the distance a—a, indicated in Fig. 90 1. The other half arc of revolution indicated by the arrow u (Fig. 1^a) completes one throw of the picker stick.

95 The travel of picker stick to the left, as shown in dot and dash lines, in Fig. 1, is accomplished by picker stick drive. The return travel, as indicated in Fig. 1^a is accomplished by the force exerted by the unwinding of torsion spring 11.

100 The embodiment shown is to be understood

as illustrative and capable of variation. It is, however, a convenient and practical form.

What I therefore claim and desire to secure by Letters Patent is:

1. In a parallel picker stick motion, a base having a stud, a picker stick strap pivoted on said stud and having a slidable connection with said base, a spring box comprising complementary members including a relatively rotatable compensating cover on said stud and a relatively stationary spring housing, and a coil spring disposed within the housing and anchored at one end to the housing and at its other end to said cover.
2. In a parallel picker stick motion, a base having a stud, a picker stick strap pivoted on said stud and having a slidable connection with said base, a spring box comprising complementary members including a relatively rotatable compensating cover on said stud and a relatively stationary spring housing, and a coil spring disposed within the housing and anchored at one end to the housing and at its other end to said cover, the housing being provided with an external series of spaced shoulders for tightening said spring.
3. In a parallel picker stick motion, a base having a stud, a picker stick strap pivoted on said stud and having a slidable connection with said base, a spring box comprising complementary members including a relatively rotatable compensating cover on said stud and a relatively stationary spring housing, said cover having a bolt and a sleeve projecting towards said housing and said housing having a cored sleeve projecting towards said cover and receiving said bolt and itself loosely received within said sleeve of the cover, and a spring coiled about said sleeve of the housing and anchored at one end to the housing and at its other end to said cover.
4. In a parallel picker stick motion, a base having a stud, a picker stick strap pivoted on said stud and having a slidable connection with said base, a spring box comprising complementary members including a relatively rotatable compensating cover on said stud and a relatively stationary spring housing, said cover having a bolt and a sleeve projecting towards said housing and said housing having a cored sleeve projecting towards said cover and receiving said bolt and itself loosely received within said sleeve of the cover, and a spring coiled about said sleeve of the housing and anchored at one end to the housing and at its other end to said cover, the housing being provided with an external series of spaced shoulders for tightening said spring and the sleeve of the cover being provided with a series of spaced shoulders over which the spring is drawn for tensioning the throw of the picker stick in one direction.
5. In a parallel picker stick motion, a base having a stud, a picker stick strap pivoted on said stud and having a slidable connection

with said base, a spring box comprising complementary members including a relatively rotatable compensating cover on said stud and a relatively stationary spring housing, and a coil spring within said housing and anchored at one end to the housing and at its other end to said cover, the sleeve of the cover being provided with a series of spaced shoulders over which the spring is drawn for tensioning the throw of the picker stick in one direction.

6. In a parallel picker stick motion, a base having a stud, a picker stick strap on said stud and having a slidable connection with said base, a rotary compensator mounted on said base and including a spring for yieldingly resisting rotation of said compensator in one direction, said base including a pair of lateral arms embracing said strap on each side thereof and effective to prevent twisting tendency of the picker stick.

7. In a parallel picker stick motion, a base having a stud, a picker stick strap on said stud and having a slidable connection with said base, a spring box including relatively rotatable members, a coil spring disposed within the housing and anchored at its end to said members, said base including a pair of lateral arms embracing said picker stick strap on each side thereof to maintain the strap in its plane of motion.

In testimony whereof I affix my signature.
EVARISTE E. TALBOT.
